WILLIAM H. MINER, OF CHAZY, NEW YORK.

SIDE BEARING.

1,290,058.

Specification of Letters Patent.

Patented Jan. 7, 1919.

Application filed May 31, 1917. Serial No. 171,829.

To all whom it may concern:

Be it known that we, WILLIAM A. BOCK and RICHARD G. BOCK, both citizens of the United States, residing at Chicago, Cook county, Illinois, have invented a certain new and useful Improvement in Side Bearings, of which the following is a full, clear, concise, and exact description, reference being had to the accompanying drawings, forming 10 a part of this specification.

This invention relates to improvements in side bearings.

The object of the invention is to provide a side bearing more particularly adapted 15 for use on railway cars and wherein an anti-friction member, such as a roller, is mounted in a cradle which is adapted to tilt about an axis transverse to the axis of the anti-friction member, the invention contemplat- 20 ing a simple and efficient arrangement for permitting the tilting action of the cradle referred to.

In the drawing forming a part of this specification, Figure 1 is a vertical, sectional 25 view of portions of a body bolster and a truck bolster and showing the invention in connection therewith. Fig. 2 is a top plan view of the side bearing proper, portions being broken away to prevent crowding of 30 the drawing. Fig. 3 is an end elevation of the side bearing. And Fig. 4 is a detail, sectional view illustrating more particularly the means for retaining the cradle in place and for limiting its swinging or tilting 35 movement.

In said drawing, 10 denotes the under face of a body bolster against which the anti-friction roller is adapted to bear and 11 indicates the corresponding opposite portion of 40 a truck bolster. The improved roller side bearing, designated generally by the reference A, is shown as attached to the truck bolster.

The side bearing A comprises an anti-friction roller B, a tilting or rocking cradle C, and a base member D. The base member D comprises a lower plate portion 12 seating directly on the truck bolster and having extended flanges 13 at the four corners there- 50 of to provide the necessary clearance for the rivets 14 by which the base member D is secured to the truck bolster. At its ends, the base member D is provided with a pair of up-standing walls or flanges 15—15, each 55 of which is provided on its inner face with

an arcuate slot or recess 16. The cradle C is substantially of rectangular hollow formation and at its ends near the bottom is provided with arcuate flanges 17 which slide within the said arcuate grooves 16. In this manner, it is apparent that the cradle C is adapted to tilt or rock upon the base member D and in order to relieve the flanges 17 of pressure, the base member D is provided with a pair of arcuate bearing surfaces 60 18—18 which coöperate with correspondingly curved under surfaces 19—19 of the cradle C.

The cradle C is hollow, as above described, to accommodate the anti-friction roller B, 70 the latter being preferably provided with an interior bushing 20 through which extends the supporting axle 21. The axle 21 is tapered at both ends, as indicated at 22, one of said axle ends being driven into a corresponding recess formed in one of the side walls 23 of the cradle. The opposite side wall 23 of the cradle at each side of the opening provided for the axle 21, is recessed as indicated at 24—24, to permit the insertion of a wedge shaped tool whereby the portions of metal 25—25 may be peened over 80 against the end of the axle 21 to prevent the latter from coming out.

In order to retain the cradle on the base member D, at all times and also to limit the amount of tilting, keys 26—26 are provided, the latter having turned-over heads 27 and adapted to extend down through recesses 28 provided in the base member D. The flanges 90 17 of the cradle C are recessed, as indicated at 29, the width of said recesses being greater than the width of the keys 26, the excess width being dependent upon the amount of tilting or rocking desired for the cradle C. 95 The keys are inserted when the parts of the side bearing are assembled and the lower ends 30 thereof may be bent over by any suitable tool operating from the under side of the member D so as to prevent accidental removal of the keys 26 although permitting the removal thereof at any time when the side bearing is in service in order that repairs or replacements may be made.

With the arrangement herein shown and 105 described, it is apparent that a strong and durable construction is provided and one requiring a relatively small amount of metal inasmuch as the base member D for supporting the cradle is reduced in weight substan- 110

tially to a minimum. By permitting the cradle C to tilt, as hereinbefore described, it is obvious that the surface of the anti-friction roller B will at all times accommodate itself to the inclination of the under surface of the body bolster against which it bears, assuming the roller side bearing attached to the truck bolster.

What is claimed is:

- 10 1. In a bearing of the character described, the combination with a retaining member, a hollow rectangular cradle, and a roller mounted within said cradle, of coöperating arcuate flanges and grooves on said member and cradle to permit tilting of the cradle.
- 20 2. In a bearing of the character described, the combination with a retaining member, a hollow cradle, and a roller rotatably supported from the walls of said cradle, of means for preventing separation of the cradle and said member, and coöperating arcuate bearing surfaces provided on the cradle and said member to permit the cradle to tilt.
- 30 3. In a side bearing, the combination with a retaining member having opposed arcuate grooves therein and arcuate bearing surfaces adjacent said grooves, of a hollow box-like cradle having laterally extending arcuate flanges at its ends slidable within said grooves, said cradle also having curved bearing surfaces adjacent said flanges coöperable with the bearing surfaces of the supporting member, and a roller rotatably mounted in said cradle.

4. In a side bearing, the combination with a supporting member having a pair of spaced vertically extending flanges, said flanges being provided with arcuate grooves on the inner faces thereof, said supporting member also having arcuate bearing surfaces, of a roller carrying cradle having laterally extended arcuate flanges slidable within said arcuate grooves, said cradle also having arcuate bearing surfaces coöperable with the bearing surfaces of the supporting member, and keys extending through recesses provided in said flanges of the cradle and supporting member, said keys preventing accidental removal of the cradle from the supporting member and also limiting the tilting of the cradle with respect thereto.

5. In a side bearing, the combination with a base member having curved bearing surfaces on its upper face, of a cradle mounted on said base member and having correspondingly curved bearing surfaces on its underside to permit tilting of the cradle, an anti-friction member carried by said cradle and extending above the upper surface thereof, and means passing through portions of the cradle and engaging the base member for preventing accidental disengagement of the cradle from said base member.

In witness that we claim the foregoing, we have hereunto subscribed our names this 10th day of May, A. D. 1917.

WILLIAM A. BOCK.
RICHARD G. BOCK.
